ANIMATED FIGURE CLOCK

Jacob S. Feiner, New York, N. Y.

Application December 15, 1938 Serial No. 245,814

7 Claims. (Cl. 58—129)

This invention relates to an improvement in pendulum clocks in the form of an attachment, designed to be actuated by the clock-driven pendulum and which utilizes and cooperates with the same to give motion to human, animal and other figure representations,—thus mechanically animated to attract attention and create interest and amusement.

In the present embodiment of the invention, the attachment is given the form of an added pendulum and is combined with a standard pendulum time movement to convert the same into a double pendulum clock, in which the pendulums move in opposite directions. This reverse oscillation of the pendulums, while here utilized to give motion to the feet of a figure representation of a girl, in simulation of the human foot movement in walking or dancing, may be readily adapted, as will be evident, to move any other part or parts of this or any other figure preferred.

Experiment and test have demonstrated that the standard pendulum time movement is ordinarily incapable of operating satisfactorily when burdened with an overload of added moving parts, unless such parts are so constructed and mounted that their weight and the friction developed in their operation is reduced to a point amounting to practical elimination.

To meet the above requirements, the weight of the pendulum and its pivotal mounting in my attachment, is carried and entirely supported by a bracket arm extension of the clock movement frame and the bearings of the pendulum are practically frictionless.

The only connection between the pendulums of the clock and the attachment, is in the form of a pin drive, the pin being carried by the clock pendulum and arranged in engaging relation with either the outer edge of the attached pendulum or the side wall of a slot or other suitably shaped opening or notch therein. Excepting when an impulse is given the attached pendulum which occurs at the end of every second oscillation, the drive pin rides clear and out of close frictional contact with the same.

To further reduce the overload, the feet and leg extensions of the girl's figure are formed as disconnected parts, one being attached to each pendulum. They have no appreciable weight, being cut out of appropriately colored light-weight paper and offer no apparent hindrance to the movement of the pendulums, as operated by the clock.

Continuous use of my attachment in connection with a standard pendulum time movement,

has satisfactorily demonstrated the successful reduction of the overload to the point of insuring practical operativeness of the combined mechanism.

Other features of the invention not specially mentioned above, will be pointed out in the detail description that follows:

Several constructions suitable for carrying my invention in effect are illustrated in the accompanying drawings but I do not wish to be understood as intending to limit myself to the same, as various changes may be made in both the form and/or details, without departing from the spirit and scope of the invention, as outlined in the appended claims.

In the drawings:

Fig. 1 is a view in front elevation of a "walking" clock, constructed in accordance with my invention.

Fig. 2 is a side elevation of the same.

Fig. 3 is a rear elevation of a standard pendulum time movement, showing my attachment operatively associated therewith.

Fig. 4 is a side elevation thereof.

Fig. 5 is a detail perspective view of the two pendulums and the connection between them.

Fig. 6 is a similar view of a modified form of the connection, and

Fig. 7 is a like showing of a further modification.

Referring now to the drawings, 1 indicates a fanciful, brightly colored figure representation of a peasant girl carrying a basket. The figure is of such size as to provide suitable space in the skirt of the dress for the dial 2 of a clock located in the rear, to which the figure is secured by screws 3, 3. Excepting the feet 4, 4, and leg extensions 5, 5, therefrom, the figure is shown as a one-piece formation. The feet with the leg extensions are formed as separate parts designed to be attached to and cover the lower portions of the two pendulums with which the clock is provided, as hereinafter described and project from under the girl figure's skirt in a natural manner.

As the pendulums swing back and forth in opposite directions, the feet and leg extensions moving with the pendulums, will suggest or give an appearance of the human foot action in walking.

The clock here shown is a standard pendulum time movement and will not therefore be described in detail beyond pointing out the escape-
ment wheel 6 and its cooperating notched cylinder 7 (Figs. 3, 4 and 5) or anchor 8 (Fig. 6).

which is mounted on a shaft 9 to oscillate and either directly or indirectly transmit its oscillatory movement to the clock pendulum 10, all in a manner well known in the art.

- 5 My pendulum attachment for converting such a time movement into a two-pendulum clock consists of a bracket-arm 11, secured as an extension of the clock movement frame 12 by one of the frame bolts 13. The bracket-arm extends downwardly from the frame 12, at a suitable angle to carry pivot bearings 14, 14, for the pendulum 15 of the attachment, which bearings are below and in vertical alignment with the center about which the clock pendulum oscillates.
- 10 15 One of the pivot bearings 14 of the pendulum 15 is formed in the bracket-arm 11 and the other bearing in a shaped addition thereto, the added piece 16 being removably secured to the arm by a screw or bolt 17 and serving to form a terminal yoke containing the above described bearings in which the pivot pin 18 of the pendulum is mounted. The pivot pin 18 is fast to the pendulum and moves freely in the bearings as the pendulum oscillates, with practically no friction.
- 15 20 25 From the foregoing it will be seen that as the weight of the added pendulum and its pivotal mounting is carried and entirely supported by the bracket-arm extension, it in no way checks or hinders the normally free operation of the time movement and its oscillating pendulum. It will also be seen from the construction and mounting of the pendulum attachment, thus far described, that securing it in operative relation to the clock movement involves no change in or 30 35 modification of the movement, but leaves it intact.

The one and only link connecting the attachment for operation by the clock movement is a driving connection between the pendulums, 40 through which, as previously stated, the attached pendulum is given an impulse every second oscillation.

I have found that except for momentary contact relation when the impulse is given, the pendulums cooperate perfectly without requiring any 45 form of physical connection between them. The employment of a physical connection such as a confining slot or other form of opening for the drive pin, has no effect whatever upon their operation, if ample freedom of movement is provided in the connection to avoid friction and 50 permit ready self-adjustment thereof to the changing angularity of the pendulums on their reverse oscillation. The main, if not the only 55 purpose it serves, is to maintain the pendulums in proper relation and against displacement under abnormal conditions, such as rough handling 60 of the clocks in shipment from the factory or from place to place, but once the clock is placed in position for use and is given ordinary care, any physical connection between the pendulums ceases to function.

In transmitting motion from one pendulum to the other, a pin 19 is secured fast to the clock pendulum and positioned to periodically engage either the outer edge of the attached pendulum, as in Figs. 6 and 7 (in which it is indicated respectively by the reference characters 19a, 19c) or the side wall of a slot or other opening 20, formed therein, as in Figs. 3 and 4. The slot or opening 20 is of such relative size that the pin contacts the wall thereof only when giving an impulse to the attached pendulum.

The drive pin is located at about the midpoint 75 between the oscillating centers of the pendulums

and as this is below one center and above the other, the oscillating movement of the pendulums will be in opposite directions.

In a standard time movement such as here shown the clock pendulum receives an impulse from the escapement every second oscillation and transmits a like impulse to the attached pendulum, through the drive pin, as above described.

Fig. 6 shows the same essential elements, operating in the same manner as in Figs. 3, 4 and 5. 10

The pin 19a on the clock pendulum continues to act as the drive pin, although provided with a terminal opening 19b, which is loosely engaged by the reduced end 20a of the attached pendulum.

Figs. 3 to 6, inclusive, show a physical connection between the pendulums which serves to maintain them in operative relation and against displacement from shock, jars and rough handling generally but, as previously pointed out, this connection is not essential to the effective operation of the added pendulum. 15 20 25

Fig. 7 shows the physical connection eliminated and the drive pin 19c of the clock pendulum relatively positioned to impart impulses to the attached pendulum by periodically contacting the outer edge 20b thereof, swinging free and clear of the same at all other times.

Having described my invention, I claim:

1. A two-pendulum clock in which the pendulums move in opposite directions and one is directly driven by the clock, and a drive pin carried by and movable with the clock-driven pendulum to establish requisite periodic contact relation with an outer edge portion only of the other pendulum to impart impulses necessary to oscillate the same. 30 35

2. A two-pendulum clock in which the pendulums are arranged to move in opposite directions, one of the pendulums being driven by the clock, and a two-member connection through 40 which motion is transmitted from the clock-driven pendulum to the other pendulum to give it reverse oscillation, one member of the connection being a pin and the other member having an opening therein in which the pin has free movement and coacts with one side only thereof in transmitting motion from one pendulum to the other. 45

3. An attachment for a pendulum clock, consisting of a second pendulum, a bracket-arm extension from the clock movement frame providing a pivotal mounting for the second pendulum and a two-member connection between the pendulums through which motion is transmitted from the clock pendulum to the added pendulum 55 to oscillate the latter in the reverse direction, one member of the connection having an opening therein and the other member being in the form of a pin freely movable in the opening to effect self-adjustment of the connection to the changing 60 angularity of the pendulums in their reverse oscillation.

4. An attachment for a pendulum clock, consisting of a second pendulum, a bracket-arm extension from the clock movement frame terminating in a yoke in which the second pendulum is pivotally mounted and a pin and slot connection between the pendulums through which motion is transmitted from the clock pendulum to the added pendulum to oscillate the latter in 70 the reverse direction. 65 70

5. A two-pendulum clock in which the pendulums move in opposite directions and one is directly driven by the clock, a single member interposed between the pendulums for intermit- 75

tent transmission of motion from the clock-driven pendulum to oscillate the other pendulum, the said member being carried by and movable with one pendulum and projecting at right angles therefrom into the path of movement of the other pendulum for periodic engagement therewith when swinging in one direction only, such engagement being at a point below the pivot of one pendulum and above the pivot of the other.

6. A two-pendulum clock as defined in claim 5, in which the member interposed between the pendulums is carried by the clock-driven pendulum.

7. A two-pendulum clock as defined in claim 5, in which the member interposed between the pendulums is in the form of a drive-pin carried by the clock-driven pendulum.

JACOB S. FEINER.
